UNITED STATES PATENT OFFICE.

JESSE CLAUDE COX AND JOHN WILLIAM McCUNG, OF ANDERSON, INDIANA.

THUMB PROTECTOR.

Application filed March 13, 1922. Serial No. 543,442.

To all whom it may concern:

Be it known that we, JESSE CLAUDE Cox and JOHN Wm. McCUNG, citizens of the United States, residing at Anderson, in the county of Madison and State of Indiana, have invented certain new and useful Improvements in Thumb Protectors; and we do declare the following to be a full, clear, and exact description of the invention, such as will enable others skilled in the art to which it appertains to make and use the same.

This invention relates to an improved protector which is especially, but not necessarily designed for bracing and protecting a sprained thumb, although it is capable of use in connection with the fingers.

Athletes, especially those who indulge in football games and the like are often bothered with sprained fingers and thumbs and to fill a long-felt need, we have designed a novel protector and brace for a sprained thumb to be worn by the player while in action to brace and prevent further injury to the thumb.

It is our principal aim to devise a protector which is such in construction as to effectively support and brace the injured part, the device being sufficiently resilient to permit a limited movement of that part, whereby to permit effective use of the device by an athlete in action.

More specifically speaking, we contemplate providing a novel and practical protector of this class which embodies a band for surrounding and bracing the wrist, an adjustable circlet for the thumb which is connected with the wrist-band, and a resilient splint which extends from the wrist-band to the circlet and acts against the top of the thumb to hold it straight but yet permit a limited movement such as may be required when handling the ball.

Other objects and advantages of the invention will be apparent during the course of the following description.

In the accompanying drawings forming a part of this specification and in which like numerals are employed to designate like parts throughout the same:

Figure 1 is a perspective view of a protector constructed in accordance with this invention showing the same in position on a person's hand.

Figure 2 is a top plan view of the pro-

tector showing the flaps forming the wrist- 55 band and circlet spread out.

Figures 3 and 4 are sections taken on the lines 3—3 and 4—4 respectively of Fig. 2.

Specifically described, the improved protector comprises a wrist bracing band 1 from which a narrow piece or stretch of flexible material 2 extends, this strip being formed at its outer end with a circlet 3 designed to surround a sprained thumb. In practice, the wrist-band, narrow intermediate strip, and 60 circlet for the thumb will be formed of a single piece of leather cut to form oppositely disposed short and long flaps 4 and 5 respectively at one end which are provided with eyelets 6 at their free ends designed to be brought together to permit a thong or flexible element 7 to be laced therethrough in the manner shown. A tongue or the like 8 is stitched or otherwise secured to the main piece of leather and underlies the meeting 75 edges of the flaps 4 and 5 and serves to prevent the lacing from cutting the flesh. The circlet 3 for the thumb is formed by widening the outer end of the extension 2 to provide considerably smaller flaps 9, these flaps 80 being likewise provided with eyelets 10 through which another flexible element 11 is laced. The thumb circlet is thus rendered adjustable and is capable of fitting various sizes of thumbs. An elongated and supplemental strip of leather or the like 12 is stitched or otherwise secured to the outer face of the main leather body and this strip extends from the wrist-band to the thumb 85 encircling member and provides a pocket for 90 accommodating a strip of resilient metal 14 which functions as a splint.

A consideration of the foregoing description in connection with the accompanying drawings will be sufficient to enable persons skilled in the art to which the invention relates to clearly understand the manner of applying the device for securing effective results. Furthermore, the several advantages, 95 constructional features and objects of the invention will also be made clear. It therefore seems unnecessary to enter a more lengthy description.

Since probably the best results may be obtained with the construction and arrangement herein shown and described, this is taken as the preferred embodiment of the invention. However, we wish it understood 105

that minor changes coming within the scope of the invention as claimed may be resorted to if desired.

What is claimed is:

- 5 1. A combined wrist and thumb protector and bracing member comprising a wristband, a circlet for surrounding a sprained or injured thumb, and a resilient splint or bracing member extending from the wristband to the thumb-encircling member and acting to hold the thumb in proper position, but permitting a limited movement thereof.
- 10 2. A combined wrist and thumb bracing and protecting member formed from a single piece of flexible material having a relatively narrow intermediate portion formed at its opposite ends with flaps adapted to surround the wrist and thumb respectively, said flaps being provided at their free edges with eyelets through which a lacing is designed to be passed, and a stiffening member extending from the wrist encircling means to the thumb encircling means.

3. A combined wrist and thumb bracing and protecting member comprising a piece 25 of flexible material having a relatively narrow central portion provided at its opposite ends with relatively large and small flaps, the larger flaps being designed to encircle the wrist and the small flaps to encircle the injured thumb, all of said flaps being formed at their free edges with eyelets to permit passage of lacings, a tongue to underlie at least one of the laces, a strip of material secured to the first named piece of material 30 and providing a pocket, and a strip of resilient metal arranged in said pocket and extending from the wrist encircling means to the thumb encircling means to brace these parts, yet permitting a limited movement of 40 the thumb when the bracing member is flexed.

In testimony whereof we have hereunto set our hands.

JESSE CLAUDE COX.
JOHN WILLIAM McCLUNG.
